(57) CLAIM

The ornamental design for a ground mat for a fence post, as shown and described.

DESCRIPTION

FIG. 1 is a perspective view of a ground mat for a fence post incorporating my design.

FIG. 4 is a right-side elevation view of the ground mat for a fence post shown in FIG. 1, the left side elevation view being a mirror image.

The evenly-spaced broken line areas depict portions of the ground mat for a fence post that form no part of the claimed design.
